US00D640210S

(12) **United States Design Patent**
Kokubu et al.

(10) **Patent No.:** **US D640,210 S**
(45) **Date of Patent:** **** Jun. 21, 2011**

(54) **LIGHT EMITTING DIODE**

(75) Inventors: **Hideki Kokubu**, Kiyosu (JP);
Toshimasa Hayashi, Kiyosu (JP);
Yukihiro Demukai, Kiyosu (JP)

(73) Assignee: **Toyoda Gosei Co., Ltd.**, Kiyosu-Shi,
Aichi-Ken (JP)

(**) Term: **14 Years**

(21) Appl. No.: **29/347,360**

(22) Filed: **Dec. 14, 2009**

(30) **Foreign Application Priority Data**

Jun. 15, 2009 (JP) 2009-013485

(57) **CLAIM**

The ornamental design for a light emitting diode, as shown and described.

DESCRIPTION

FIG. 1 is a perspective view of top, rear and right side of a light emitting diode showing our new design;

FIG. 2 is a front view thereof;

FIG. 3 is a rear view thereof;

FIG. 4 is a top plan view thereof;

FIG. 5 is a bottom view thereof;

FIG. 6 is a left side view thereof;

FIG. 7 is a right side view thereof; and,

FIG. 8 is an end view at 8—8 shown in FIG. 3 thereof.

The portions of the article in broken lines are shown for illustrative purposes only and form no part of the claimed design.
